UNITED STATES PATENT OFFICE

JOSEPH JOHNSON, OF PRESCOTT, ARIZONA, ASSIGNOR OF ONE-HALF TO ELVIN R. JACKSON, OF PHOENIX, ARIZONA

ROTARY ENGINE

Application filed August 7, 1929. Serial No. 384,086.

This invention relates to rotary engines and is an improvement upon the engine disclosed in Patent #1,066,413, granted to me July 1, 1913.

5 An object of the present invention is to improve and simplify the construction of the engine so as to increase its efficiency of operation, as well as to provide means whereby its direction of rotation may be controlled.

10 Another object of the invention is the provision of means to provide a steam by-pass between the intake and exhaust ports of the engine and eliminate dead spots regardless of the position of the engine rotor, as well 15 as to provide a continuous power impulse under full steam pressure without lost motion or loss of energy.

With the above and other objects in view, the invention further includes the following 20 novel features and details of construction, to be hereinafter more fully described, illustrated in the accompanying drawings and pointed out in the appended claims.

In the drawings:

25 Figure 1 is a side elevation of an engine constructed in accordance with the invention.

Figure 2 is a section on the line 2—2 of Figure 1.

Figure 3 is a section on the line 3—3 of 30 Figure 2.

Figure 4 is a section on the line 4—4 of Figure 3.

Figure 5 is a fragmentary section taken substantially on the line 5—5 of Figure 2.

35 Referring to the drawings in detail wherein like characters of reference denote corresponding parts, the engine as illustrated includes a suitable base 10 upon which is mounted a cylindrical housing 11 whose opposite ends are closed by removable heads 12.

A concentrically arranged shaft 13 is mounted in suitable bearings 14 provided in the heads 12 and secured upon this shaft is 45 the hub 15 of a rotor 16, the rim of which is joined to the hub by means of spokes or webs 17.

The outer periphery of the rim of the rotor is spaced from the inner periphery of the 50 cylindrical housing 11. Extending from the

periphery of the rotor are spaced lugs or pistons 18 which are preferably oppositely inclined as shown at 19. These lugs or pistons are removably secured to the rotor as by dovetailed tongues and slots 20, so that if 55 desired these lugs or pistons may be re-engaged, or they may be replaced by pistons of the type disclosed in my patent above referred to.

Extending through the housing are spaced 60 ports 21 and 22. These ports are in communication with branch pipes 23 and 24, each of which is controlled by a valve 25 or 26 respectively.

Mounted for sliding movement within the 65 housing and adapted for engagement with the outer periphery of the rotor are spaced cut off abutments 27. These abutments are 70 yieldingly forced inward against the rotor by means of springs 28, so that as the rotor operates, the abutments will operatively engage the periphery of the said rotor and will ride over the lugs or pistons 18. As the lugs or pistons are reversely inclined, this 75 action of the cut off abutments will occur irrespective of the direction of rotation of the rotor.

Extending laterally from opposite sides of the rotor chamber are diametrically located by-pass passages 29 whose opposite 80 ends communicate with the ports 21 and 22. The lugs or pistons 18 are equal in length to the width of the rotor chamber as shown in Figure 4 of the drawings, while the cut off abutments 27 are of greater width than the 85 width of the rotor chamber so that the ends of these abutments extend into the by-pass passages 29.

The engine may operate in either direction. When operating in an anti-clockwise direction as in Figure 3 of the drawings, steam (or water as the case may be) enters through the ports 21, the valves 25 being open and the valves 26 of these ports being closed. Conversely, the valves 26 of the ports 22 are 95 open and the valves 25 of these ports closed.

By reference to Figure 3 it will be seen that steam entering through the ports 21 will expand between the adjacent cut off abutment 27 and the adjacent lug or piston 18, so that 100

the rotor will be forced in an anti-clockwise direction until the lug or piston reaches the port 22, through which it will exhaust. Steam will be prevented from passing the cut off abutments 27 as these abutments extend 5 into and close the by-pass passages.

By reversing the valves 25 and 26, the rotor may be operated in a reverse direction.

It will be apparent that during the operation of the engine, the lugs or pistons 18 follow one another in rapid succession so that 10 live steam is continuously imparting an impulse to the rotor. When the slide abutments 27 are moved inward they completely cut off the by-pass passages, but when moved 15 outward through the medium of the lugs or pistons 18, live steam passes under the edges of these slide abutments. The crown of the lugs or pistons never covers more than approximately one-third of the ports and only 20 a portion of the live steam at the intake port is spent in backing into the expansion chambers defined by the lugs or pistons 18 and the slide abutments 27. The steam then re-acts 25 on the lug or piston and prevents back pressure.

The invention is susceptible of various changes in its form, proportions and minor details of construction and the right is herein reserved to make such changes as properly fall within the scope of the appended claims.

Having described the invention what is claimed is:—

1. In a rotary engine, a cylindrical casing having spaced ports defining inlet and exhaust ports, a cylindrical rotor concentric with and of less diameter than the inner periphery of the casing, reversely inclined pistons carried by the rotor and engaging the inner periphery of the casing, spaced spring pressed cut off members slidably mounted in the casing adjacent each of the ports and defining with the pistons, expansion chambers, and spaced diametrically located by-pass passages formed in the casing, each of said passages having their opposite ends in communication with two of the ports.

2. In a rotary engine, a cylindrical casing having spaced ports defining inlet and exhaust ports, a cylindrical rotor concentric with and of less diameter than the inner periphery of the casing, pistons carried by the rotor and engaging the inner periphery of the casing, spring pressed cut off members slidably mounted in the casing and defining together with the pistons, spaced expansion chambers, and a by-pass passage provided within the casing between and communicating with the inlet and exhaust ports.

60 3. In a rotary engine, a cylindrical casing having spaced ports defining inlet and exhaust ports, a cylindrical rotor concentric with and of less diameter than the inner periphery of the casing, pistons carried by the 65 rotor and engaging the inner periphery of

the casing, spaced spring pressed cut off members slidably mounted in the casing adjacent each of the ports and defining together with the pistons, spaced expansion chambers, by-pass passages located within the casing and extending laterally from and communicating with the expansion chambers, said passages having their opposite ends in communication with the inlet and exhaust ports, and said cut off members having their opposite ends extending into the by-pass passages to close the same.

In testimony whereof I affix my signature.
JOSEPH JOHNSON.
